WILLIAM G. DEMAREST, OF PLAINFIELD, NEW JERSEY

BUILDING BLOCK AND WALL CONSTRUCTION

Application filed November 23, 1928. Serial No. 321,357.

This invention relates to building block and wall construction, and has for its primary object and purpose to provide a block of terra cotta, concrete or other material to constitute 5 the backing or inner lining for a brick wall which is of such construction that when incorporated in the wall and bonded with the outer brick the mortar joints between adjacent block and between said block and the 10 header courses of brick will be broken by dead air spaces of appreciable area to thereby afford an effective protection for the interior of the building against the action of frost, fire, water, wind, etc.

15 In carrying out this essential object and purpose of my present invention, I provide a block having one bearing side which includes a section forming a joint with the header brick and a laterally and vertically offset section having a depth substantially equal to one-half the depth of a brick course.

The other bearing side of the block also has spaced sections, but the bearing surfaces thereof are disposed in the same horizontal 25 plane, said surfaces being separated by an intervening continuous longitudinal channel. When the block or blocks of this construction are laid up to form the backing or lining wall, the said channels of the adjacent block 30 opposed to the stretcher courses of brick are in mating relation and form a continuous horizontally extending dead air space interrupting the mortar joint between the spaced bearing surfaces at the opposed sides of said blocks.

35 The opposite laterally and vertically offset bearing sections of adjacent blocks are opposed to the inner ends of the header bricks in one course and likewise form longitudinally extending dead air spaces interrupting the mortar joint between the offset bearing sections of the block and the bearing sections at the same sides of the blocks which are opposed to the header brick and bonded 40 therewith. In this manner, it will be evident that the transmission of moisture through the wall structure to the inner side thereof is effectually precluded, since there are no continuous mortar joints through 45

50 which moisture might be transmitted extend-

ing between the outer and inner faces of the wall.

It is also an object of the invention to provide a wall structure composed in part of my novel form of blocks which may be erected quickly and with a minimum of manual labor and which will also provide a building wall which will satisfactorily meet municipal building codes as to resistance to stress or strains.

It is another object of my invention to provide a building block in which the sides defining the dead air spaces when in combination with similarly made blocks to form a wall structure, will have grooves or nicks 65 extending the length of the block whereby to prevent the creeping of moisture or water from the mortar on one part of the joined blocks to the mortar bond disposed on the other side of the joined blocks.

70 It is also an additional object of the invention to provide a building block having the above noted advantages when embodied in a wall structure and which is so formed that the blocks can be compactly stacked so that they 75 will not be liable to excessive damage or injury in shipment.

75 With the above and other objects in view, the invention consists in the improved building block and wall construction as will be 80 hereinafter more fully described, illustrated in the accompanying drawing and subsequently incorporated in the subjoined claim.

In the drawing, wherein I have illustrated one simple and practical embodiment of the 85 invention, and in which similar reference characters designate corresponding parts throughout the several views,—

Figure 1 is a fragmentary vertical section of a building wall showing one embodiment 90 of my new block as employed in connection with a common six course brick wall generally referred to as an English bond, and

Figure 2 is a detail perspective view of one 95 of the blocks.

For purposes of illustration, I have shown the outer brick wall as composed of the vertically spaced courses of header brick 5 and a plurality of intervening courses of stretcher brick 6. These brick are of standard dimen- 100

sions, and in the present instance, I have shown five courses of the stretcher brick 6 interposed between the spaced header brick courses 5. The brick courses are securely 5 bonded together by the usual mortar joints indicated at 7.

My improved block which forms the backing or inner lining of the outer brick wall and renders the interior of the building proof 10 against the passage of fire or water therethrough, consists essentially of two hollow sections 8 and 9 respectively, separated by a common wall or web 10. The section 8 is of true rectangular form, the opposite bearing 15 sides thereof having the joint forming surfaces indicated at 11 which extends across the full width of said block section. At one bearing side of the block, the section 9 thereof has a joint forming surface 12 positioned in 20 the same plane as the surface 11 of the block section 8 but spaced therefrom by an intervening longitudinally extending channel 13. The side 12 of the block section 9 is connected with the wall 10 by the obliquely inclined 25 web 14. In order to break the curvature of the web 14, a straight faced portion 13' is provided which extends from the side 12 to the inclined web 14 thereby forming a nick or groove 13'' extending the length of the block. 30 The nick breaks the advance of the creeping action of water or moisture contained or absorbed by the mortar 7' when the blocks are joined to form a building wall, as shown in Fig. 1.

35 At the other bearing side of the block, the section 9 thereof is provided with a lateral vertical offset integrally connected with the wall 10 by the web 15 obliquely inclined in an opposite direction with respect to the web 14. 40 The web 15 and the joint forming surfaces 11 and 16 are joined by means of the straight faced portions 16' and 11' to form the nicks 16'' and 11'' respectively. It will be noted that such nicks or grooves on the block pre- 45 vent the creeping or flow of water from the mortar 7' toward the flat surface 9. The nicks are disposed along the length of the block and are uniformly cut for effectively collecting the moisture in its creeping action. 50 and as soon as any perceptible quantity of moisture collects in the grooved portion, it drops down to the bottom of the air space formed by joining the blocks, as shown in Fig. 1 of the drawing. This offset portion of the 55 block section 9 provides a joint forming surface 16 corresponding to the surface 12 but which is disposed out of the plane of the surface 11 on this side of the block. The offset on this bearing side of the block is substantially equal to half of the depth of one course of brick.

60 After the brick wall has been erected, the blocks are arranged as shown in Fig. 1 of the drawing, the rectangular sections 8 of adjacent blocks being positioned in superposed

relation between the spaced header brick courses 5 and with the spaced bearing side surfaces 11 and 12 of the blocks opposed to each other while the surfaces 11 at the opposite bearing side of the block sections 8 are opposed to the header brick 5.

The mortar joints 7 between the brick courses are continued between the adjacent block sections 8 and between said section and the header brick 5 as shown at 7'. This multiple arrangement of the hollow blocks between the inner ends of the header brick course 5 is continued throughout the height of the wall so that it will thus be seen that the offset bearing side sections 16 of the blocks extend over and are inwardly spaced from the inner ends of the header bricks 5. These bearing sections of the blocks are bonded together by the mortar joints 17. The converging webs 15 of adjacent blocks which join the spaced bearing side portions 11 and 16 with each other, thus form a continuous dead air space 18 of appreciable area between the inner ends of the mortar joints 7' and the header bricks 5 and the mortar joints 17. Likewise the converging webs 14 of the blocks which are interposed between the vertically spaced header brick courses also form longitudinally extending dead air spaces 19 which separate the mortar joints 7' between the opposed bearing surfaces 11 of the blocks from the mortar joints 20 between the opposed bearing surfaces 12 of the inner portions 9 of the building blocks. It will thus be evident that by the provision of such continuous dead air spaces 18 and 19 extending horizontally throughout the building wall and completely breaking the connection between the mortar joints bonding the inner portions 9 of the blocks together and the joints between the outer portions 8 of said blocks, all possibility of the seepage of moisture through the mortar joints from the outer side of the building wall to the inner side thereof is precluded. Also such dead air pockets, in addition to the hollow block sections increase the effectiveness of the wall structure against the transmission of hot and cold air currents therethrough.

It will be evident that with a hollow building block of the above construction, the wall may be easily and quickly erected and while the weight of the blocks is relatively low, the wall structure will possess high resistance to stress or strain. In the illustrated embodiment of my invention, I have shown the new blocks as applied to a brick wall having five courses of the stretcher brick, but it will be understood that the block may be made in other dimensions so that it may be employed in connection with a less number of courses of the stretcher brick. In the brick wall structure shown in connection with the block described herein, it will be noted that the

nicks or grooves provided adjacent the ends of the webs of the block are useful as water or moisture traps. This feature is particularly notable in the upper webs of the blocks 5 when such blocks are joined together, as shown in Fig. 1, to form the dead air spaces 18 and 19. For example, as the moisture creeps from the mortar 7' along the straight faced portion 11' of the top block 9 it reaches 10 the nick 11'' whereupon it drops to the bottom of the air space. If some of the moisture does creep along the web 15 to the next nick or groove 16'' most of it will have dropped to the bottom of the air space. In this 15 manner moisture is prevented from reaching the mortar 17 and thence into the room defined by the walls 9 of the blocks. It is also apparent that certain variations may be resorted to in the structural form of the detail parts of the block, and it is accordingly 20 to be understood that in practice the privilege is reserved of resorting to all such legitimate changes therein as may be fairly incorporated within the spirit and scope of the invention 25 as claimed.

I claim:

In a hollow building block having two sections joined together to form a unitary structural piece, both sections having aligned 30 bearing surfaces at one end and transposed bearing surfaces at the other end, one bearing surface being raised above the other substantially half the depth of a header brick, the improvement which consists in two curvate walls in one section disposed between the end bearing surfaces of both sections, said curvate walls having nicks at the ends thereof, and straight faced portions interposed between the walls and the adjacent 35 bearing surfaces, said curvate walls forming, when a plurality of blocks are superposed upon each other, symmetrical dead air spaces of identical configuration at each end of the blocks with the binding mortar of the bearing 40 surfaces of smaller layer section forming a median line in the plane of symmetry of 45 said dead air spaces.

In testimony that I claim the foregoing as my invention, I have signed my name 50 hereto.

WILLIAM G. DEMAREST.
